UNITED STATES PATENT OFFICE

JOHN SINKO, OF CHICAGO, ILLINOIS

CIGAR LIGHTER

Application filed October 31, 1928. Serial No. 316,164.

This invention relates to electric cigar lighters of the class used on automobiles, and has reference more particularly to a type of such lighters commonly known as "wireless" lighters, which are characterized by the provision of a socket member mounted on the dash or other part of the car body and carrying a contact terminal wired to the battery and a plug member comprising a hand-piece carrying an igniter element and a cooperating contact terminal, the plug member being moved in the socket member to close the circuit through said contact terminals and held in such position until the igniter element has become heated to incandescence, and then removed from the socket member for use.

One object of the present invention is to provide a wireless cigar lighter of very simple and inexpensive construction, wherein the circuit is normally maintained open by a spring in the socket member exerting an outward thrust on the plug member, and is closed by a slight inward movement of the plug member. Another object is to provide a construction wherein the spacing between the contact terminals carried by the socket member and the plug member, respectively, can be nicely and accurately adjusted. Another object is to provide a construction affording a comparatively short total length of combined socket and plug so that the lighter will not project to an objectionable length into the interior space of the car. Still another object is to provide a cigar lighter, the socket member of which shall be adapted to receive the plug of a service or trouble light and to automatically maintain the circuit closed when said last-named plug has been inserted.

My invention, its manner of use, and the advantages inhering therein will be readily understood by persons skilled in the art from the following description, taken in connection with the accompanying drawings, in which I have illustrated one simple and practical embodiment, and wherein—

Fig. 1 is an axial sectional view of the lighter and its supporting bracket; 50 Fig. 2 is a similar view, in a plane at right

angles to that of Fig. 1, and showing the igniter-carrying element in side elevation;

Fig. 3 is a front elevation;

Fig. 4 is a sectional elevation in the same plane as that of Fig. 2, illustrating the application of a service or trouble light plug;

Fig. 5 is a perspective detail view of a spring plate which carries the inner contact member.

Referring to the drawings, 10 designates 60 as a whole a U-shaped attaching bracket, the forward upstanding limb 10^a of which carries the lighter, and the rear upstanding limb 10^b of which carried a binding screw 11 by which the bracket may be clamped on the lower edge of an instrument board. The lower horizontal limb of the bracket is preferably slotted, as shown, to facilitate the passage of a circuit wire.

Mounted on the circular rim of the front bracket limb 10^a is a metal shell 12 formed with an inwardly curled front marginal stop flange 13. Within the shell 12 and abutting at its outer end against the flange 13 is a cup-shaped member 14 formed with a front marginal flange 15. Confined between the flange 15 and the bracket limb 10^a is a thrust spring 16.

The bottom wall of the cup-shaped member 14 is formed with a central aperture into which is swaged the inner end of a cylinder 17. In the inner wall of cylinder 17 are a 70 pair of oppositely disposed bayonet slots 18 for a purpose hereinafter described.

19 designates a contact carrier, preferably 75 taking the form of a slightly bowed or arched spring plate, the ends of which are inserted beneath the inner coil of spring 16 and bear against the bracket limb 10^a, as shown in Fig. 2. Spring plate 19 is formed with a 80 circular laterally-offset central portion 20 in which is a hole 21. Passed through the hole 21 is a contact stud 22 having a shank of less diameter than, and out of contact with the edge of, hole 21, and supported by fiber washers 23 and 24. To the rear end of contact stud 22 is connected a circuit line 25 from the positive pole of the battery, line 25 being 85 conveniently entered through the slot in the lower limb of bracket 10. To lock the con-

90
95
100

tact carrier plate against turning and imposing a strain on the fastening of circuit wire 25, the plate 19 is preferably formed near its ends with slots 26 (Fig. 5), through which extend lugs 27 cut and bent outwardly from the bottom wall of the cup-shaped member 14. The bracket limb 10^a is formed with holes 28 opposite the lugs 27 which are entered by the latter when the cup-shaped member is 10 pressed inwardly to close the circuit, as hereinafter described.

The parts thus far described are all permanently mounted on and carried by the bracket 10.

15 Describing now the removable plug element of the lighter, 29 designates a hand piece of bakelite, hard rubber, or other like material having the general form of a telephone transmitter mouth-piece and formed with an internal annular-rib 30. Crimped on the rib 30 is the outer end of another metal cup-shaped member 31, the inner or bottom wall of which has a laterally offset portion 32 formed with a central aperture 33 through 20 which, and out of contact with the edge of aperture 33, extends a tapped contact stud 34 supported by a fiber washer 35. Stud 34 has a kerf in its head for application and adjustment by a screw driver. Seated in the 25 open front end of the member 31 is a shallow igniter carrier 37 formed with a marginal flange 38 on its outer end overlapping the outer end of the member 31 and the rib 30. The igniter carrier 37 has a central hole 38 through which extends with clearance a 30 screw 39 supported by fiber washers 40 and 41 that are clamped on carrier 37 by a brass washer 42 and nut 43, the inner end of said screw entering the tapped contact 34. The 40 head of screw 39 is slotted to receive the inner end of the spiral igniter element 44, the outer end of the latter being electrically connected to the rim of the carrier 37, which latter lies in contact with member 31.

45 In operation, the spring 16 normally maintains the contacts 22 and 34 separated. To heat the ignition coil 44, the hand-piece 29 is pressed inwardly, compressing spring 16, and closing the circuit between contacts 34 and 22, the circuit being grounded on bracket 10 through parts 37, 31, 17, 14, and spring 16. The hand-piece is held pressed in until the coil is incandescent, when it is pulled out of the socket and used. When replaced, spring 50 16 separates the contacts 34 and 22 as soon as the hand is removed from the hand-piece 29.

For purposes of a cigar lighter alone, the contact carrier plate 19 need not be a spring, but might be a rigid flat plate, all 55 though, the spring support insures better contact. Its spring form well adapts the socket portion of the device for service with the plug of a service or trouble light. This capacity of the device is illustrated in Fig. 4, wherein the cigar lighter plug has been

70 withdrawn and replaced by the plug 50 of a service light, the cords of which are indicated at 51. The shank 50' of plug 50 is provided with short pins or lugs 52 that enter the bayonet slots 18 and lock the plug in place. On the inner end of the plug is a contact button 53 that strikes the contact 22 before the pins 52 enter the offset ends of the bayonet 75 grooves 18, and as the plug is pushed in far enough to lock the pins 52 in the bayonet grooves, the spring contact plate 19 is flexed toward a flat condition, thus insuring snug engagement of the contacts 53 and 22 with each other while the lamp is in service.

By reason of the fact that in the described 80 structure, the thrust spring 16 is so arranged that for the greater part of its length it occupies a telescopic relation to the removable plug element, it is possible to position the two contacts very close to each other so that but 85 a slight inward movement of the plug element suffices to close the circuit, and this arrangement also affords a very short total length of continued socket and plug.

It will also be noted that the spacing of 90 the cylinder 17 from the portion of the hand piece 29 surrounding the same provides an annular air space between the two that serves as a heat insulation for the hand piece. The 95 bayonet slots 18 enable the cylinder 17 to expand slightly as the plug member 31 is forced therein, whereby the latter is yieldably held in place under a spring friction, and is not liable to be jarred loose and fall out of the socket.

100 I claim:

1. In a wireless cigar lighter, the combination of a socket member including an outer shell formed with an internal stop flange on its forward end and a cup-shaped member within said shell abutting at its outer end against said flange, a spring in said shell urging said cup-shaped member outwardly, a circuit contact terminal disposed in rear of said cup-shaped member, a plug member insertible in said cup-shaped member, a circuit contact terminal mounted on the inner end of said plug member, and an igniter element mounted on said plug member and electrically connected to said last-named terminal. 105

2. In a wireless cigar lighter, the combination of a socket member including an outer shell formed with an internal stop flange on its forward end and a cup-shaped member within said shell abutting at its outer end against said flange, said cup-shaped member having an external annular flange on its outer end, a coil spring in said shell encircling said cup-shaped member and abutting against said annular flange, a circuit contact terminal disposed in rear of said cup-shaped member, a plug member insertible in said cup-shaped member, a circuit contact terminal mounted on the inner end of said plug member, and 110 115 120 125 130

an igniter element mounted on said plug member and electrically connected to said last-named terminal.

3. In a wireless cigar lighter, the combination of a socket member including an outer shell formed with an internal stop flange on its forward end, a centrally-apertured cup-shaped member within said shell abutting at its outer end against said flange and having an external annular flange on its outer end, and a metal cylinder mounted at its inner end in the central aperture of said cup-shaped member, a coil spring in said shell encircling said cup-shaped member and abutting against said annular flange, a circuit contact terminal disposed in rear of said cup-shaped member, a plug member comprising a hand-piece of insulating material telescoping within said cup-shaped member and a metal contact carrier telescoping within said metal cylinder, a contact terminal on the inner end of said contact carrier opposite said first-named contact terminal, and an igniter element mounted on the outer end of said plug member and electrically connected to the terminal on said contact carrier.

4. As a new article of manufacture, a socket member for the purposes described, comprising an outer shell formed with an internal stop flange on its forward end, a centrally-apertured cup-shaped member within said shell abutting at its outer end against said flange, a spring within said shell urging said cup-shaped member outwardly, a spring

plate in said shell in rear of said cup-shaped member, a contact terminal carried by said spring plate, and a cylinder mounted in the central aperture of said cup-shaped member and formed with a bayonet slot therein.

5. As a new article of manufacture, a socket member for the purposes described, comprising an outer shell formed with an internal stop flange on its forward end, a centrally-apertured cup-shaped member within said shell abutting at its outer end against said flange and formed with an external annular flange on its outer end, a coil spring in said shell encircling said cup-shaped member and abutting against said annular flange, a spring plate in said shell in rear of said cup-shaped member, a contact terminal carried by said spring plate, and a cylinder mounted at its inner end in the central aperture of said cup-shaped member and formed with a bayonet slot therein.

6. In a wireless cigar lighter, the combination with a socket member, and a contact terminal therein, of a plug member telescopingly engaged with said socket member, an igniter element mounted in the outer end of said plug member, a screw mounted in said plug member to the outer end of which said igniter element is electrically connected, a second contact terminal having a tapped bore engaged with the inner end of said screw

and disposed opposite said first-named contact terminal, and a spring in said socket member normally holding said contact terminals separated from each other.

7. In a wireless cigar lighter, a removable plug member adapted for telescopic engagement with a fixed socket member, comprising a hollow hand piece of insulating material formed with an internal annular rib, a metal sleeve member at its outer end crimped on said rib, an ignition element mounted in the outer end of said sleeve member, a screw disposed coaxially with said sleeve member and at its outer end electrically connected to said ignition member, and a contact stud mounted on the other end of said screw.

8. In a wireless cigar lighter, a removable plug member adapted for telescopic engagement with a fixed socket member, comprising a hollow hand piece of insulating material formed with a flaring outer end portion and an internal annular rib, a metal sleeve member at its outer end crimped on said rib, a shallow cup-shaped igniter carrier formed with a marginal flange on its outer end overlapping the outer end of said sleeve, an igniter element seated in said igniter carrier with one end thereof electrically connected to the latter, a screw disposed coaxially with said sleeve member extending through said igniter carrier and electrically connected to the other end of said igniter element, and a contact stud mounted on the inner end of said screw.

JOHN SINKO.
